UNITED STATES PATENT OFFICE.

ELMER HODGSON, OF BONESTEEL, SOUTH DAKOTA.

SURFACING-TOOL.

No. 851,518.

Specification of Letters Patent.

Patented April 23, 1907.

Application filed May 2, 1906. Serial No. 314,875.

To all whom it may concern:

Be it known that I, ELMER HODGSON, a citizen of the United States, residing at Bone-
steel, in the county of Gregory and State of
South Dakota, have invented certain new and
useful Improvements in Surfacing-Tools, of
which the following is a specification.

This invention relates to an improved sur-
facing tool and is designed more particularly
for the scraping and sand papering of floors
or similar surfaces.

The object of the invention is to provide a
tool of this character which can be used with
equal facility either as a scraper or as a sand
papering machine.

A further object is to so construct the de-
vice that the angle of the scraping blade can
be regulated with relation to the floor, ac-
cording to the character of material being
operated upon.

For a full description of the invention and
the merits thereof, and also to acquire a
knowledge of the details of construction of
the means for effecting the result, reference
is to be had to following description and ac-
companying drawings, in which:

Figure 1 is a perspective view showing the
device as being employed as a floor scraper;
Fig. 2 is a transverse sectional view showing
the support; Fig. 3 is a sectional view through
a portion of the device and shows the method
of attaching the support.

Corresponding and like parts are referred
to in the following description and indicated
in all the views of the drawings by the same
reference characters.

The stock or body of the tool comprises
two plates 1 and 2, which are preferably
formed of metal and which are shown in the
drawings as having an approximately rectan-
gular shape. Each of the plates 1 and 2 is
provided with a pair of parallel slots 3 which
are so formed as to register when the two
plates are brought together. The bit or
scraping blade 4 is located between the plates
1 and 2 and is held in position by means of
bolts or other fastening means 5 which pass
through openings in the scraping blade and
are slidably mounted within the slots 3.
One end of the scraping blade 4 is formed
with a beveled edge 6 and the blade can be
moved back and forth between the plates 2
so as to cause the beveled edge to project
outwardly the desired distance. The upper
plate 1 is provided with a lug or projection 7
by means of which the handle 8 is connected

to the tool. Metal plates 9 fit upon opposite
sides of the lower end of the handle 8 and
project beyond the same so as to embrace the
lug 7. A bolt or pivot pin 10 is passed 60
through the projecting portion of the plates
9 and the lug 7, and the faces of these mem-
bers which come into contact with each other
are preferably provided with radial corruga-
tions 11. It will thus be seen that by loosen- 65
ing the bolt 10, the handle can be thrown to
any desired angle and can then be securely
clamped in that position. The lower plate 2
is formed at one end with a transversely dis-
posed and downwardly projecting flange 12 70
which serves as a securing means for the sup-
port 13. This support 13 is preferably
formed of soft or resilient material such as
rubber so that there will be no danger of
denting or otherwise marring the surface be- 75
ing operated upon, and in the present in-
stance, the support comprises a block or rod
14 which is surrounded by a rubber covering
15. The edges of the covering are clamped
securely against the downwardly projecting 80
flange 12 by means of a metal strip 16 which
is held in position by bolts or similar fasten-
ing means.

A roller 17 is secured to the tool at the
scraping end thereof and for this purpose a 85
pair of arms 18 are provided which are se-
cured to the top of the upper plate 1 and pro-
ject beyond the end thereof. These arms 18
are preferably formed of metal strips, one
end of each of which is slotted and held in po-
sition against the plate 1 by a bolt 19, while
the opposite end is longitudinally twisted
so as to form a bearing for the roller 17. 90
Owing to the fact that the inner ends of the 95
arms 18 are slotted, it will be apparent that
they can be adjusted so as to regulate the
amount the roller projects beyond the plate
1. The bolts 19, by means of which the
arms 18 are held in position, are preferably 100
located at one end of the slots 3 and are pro-
vided with heads which are counter sunk so as
to lie flush with the lower face of the upper
plate 1. When it is desired to employ the
device as a scraper, the bit 4 is adjusted so 105
that the beveled edge 6 thereof projects the
desired amount from the plates 1 and 2 and
the roller 17 is adjusted so as to throw the
scraping blade 4 at the desired angle to the
floor. In this connection, it will be readily 110
understood that when the roller 17 is brought
toward the plate 1, the scraping blade 4 will

be thrown at a greater angle to the floor and vice versa. While using the tool in this capacity the support 13 which is formed of soft material will prevent the metal plates or 5 the bolts therein from coming into contact with the floor in such a manner as to dent or otherwise mar the same.

Having thus described the invention, what is claimed as new is:

- 10 1. In a surfacing tool, the combination of a pair of plates, a scraping blade mounted between the plates, a roller mounted upon one of the plates and engaging with the surface to hold the scraping blade at the desired angle, 15 and a support secured to the opposite plate and serving to prevent any injury to the surface being operated upon.
- 20 2. In a surfacing tool, the combination of a pair of plates, a scraping blade mounted between the plates, a pair of arms adjustably connected to one of the plates, a guide roller mounted between the two arms and serving to regulate the inclination of the scraping blade to the surface, and a support secured 25 to the opposite plate and serving to prevent injury to the surface being operated upon.
- 30 3. In a surfacing tool, the combination of a pair of plates, a scraping blade mounted between the plates, a pair of arms projecting beyond the edge of one of the plates and formed with slots, fastening members passing through the slots and serving to secure the arms to the plate, the slots permitting the arms to be moved back and forth, a guide roller journaled between the arms and serving 35 to regulate the inclination of the scraping blade to the surface, and a support secured to the opposite plate.
4. In a surfacing tool, the combination of a

base comprising a pair of plates, a scraping blade adjustably mounted between the plates, a pair of arms projecting laterally beyond one edge of one of the plates, the said arms being formed with longitudinal slots and being secured to the plate by fastening 45 members passing through the slots so as to be readily moved back and forth, a guide roller journaled between the two arms and serving to regulate the inclination of the scraping blade to the surface, and a handle adjustably 50 connected to the plate.

5. In a surfacing tool, the combination of a pair of plates, a scraping blade mounted between the plates, a guide roller mounted upon one of the plates and serving to hold the 55 scraping blade at the desired angle to the surface, a transverse rib upon the opposite plate, and a support secured to the transverse rib and tending to prevent any injury to the surface.

6. In a surfacing tool, the combination of a base comprising two plates, a scraping blade adjustably mounted between the plates, a pair of arms projecting laterally from one of the edges of the plate and adjustably connected to the plate so as to be movable back and forth, a guide roller journaled between the two arms and serving to regulate the inclination of the blade to the surface, a transverse rib located upon the opposite plate, and 70 a support secured to the transverse rib and tending to prevent any injury to the surface.

In testimony whereof I affix my signature in presence of two witnesses.

ELMER HODGSON. [L. S.]
